UNITED STATES PATENT OFFICE.

JACOB S. SMITH, OF CHICAGO, ILLINOIS.

METHOD OF PRODUCING HEATING AND ILLUMINATING GAS.

No. 833,346.

Specification of Letters Patent.

Patented Oct. 16, 1906.

Application filed February 13, 1905. Serial No. 245,337.

To all whom it may concern:

Be known that I, JACOB S. SMITH, a citizen of the United States, residing at Chicago, in the county of Cook and State of Illinois, have 5 invented certain new and useful Improvements in Methods for Producing Gas for Heating and Illuminating Purposes, of which the following is a full, clear, and exact specification.

10 This invention relates to improvements in methods for manufacturing gas for heating and illuminating purposes from liquid hydrocarbons, steam, and air, and particularly the first two of these materials.

15 The prime object of my invention is a process by which the gaseous elements of gas-producing materials are so thoroughly dissociated and reassociated, combined, and fixed in gas for use that it may be washed, filtered, 20 compressed, stored, transported, and distributed in pipes and mains for use without, as near as may be, deterioration in either quality or volume, and this particularly with gas produced from oil, steam, and air.

25 A further object is a process by which a maximum quantity or volume of steam may be dissociated into its gases with an absence of an excess of carbon dioxid and nitrogen, while at the same time the liberated hydro- 30 gen is intimately mixed and combined with volatilized carbon.

Another object of my invention is a 35 method for controlling and uniformly maintaining a gas-producing temperature in a generator by adding to or subtracting from the supply of one or all of the gas-producing materials to the generator, and at the same time to utilize the heats of the evolved gases to decompose additional steam, and this at 40 such a point relative to the place of decomposition of the previously-produced gases as to promote the perfect combination of the gases from said excess of steam with the previously-evolved hydrocarbon gases.

45 A still further object is a method by which the decomposition of gas-producing materials into their gaseous elements is substantially quickened, the quantity of material to sustain a decomposing heat therefor is substantially reduced, and the volume of fixed 50 gases from a given quantity of gas-producing materials is substantially increased.

55 A further object is a method by which heavy hydrocarbons and other refuse materials are largely removed and discharged

from the gas before the scrubbing operation takes place, and also by which after the scrubbing operation the gas is so thoroughly filtered as to prevent thereafter any substantial deterioration either in quantity or quality of the gas when subsequently compressed, stored, transported, and distributed.

In carrying out my invention I preferably employ the apparatus illustrated in the accompanying drawings; but, as will be made 65 apparent later on, my invention is not limited or confined to the details of construction therein shown, but may be performed with equal success in an apparatus which, mechanically speaking, is substantially different therefrom.

In the accompanying drawings, Figure 1 illustrates a central vertical section of an apparatus, and Fig. 2 a side elevation, partly in section, of a compressor in and by which the invention of my methods may be performed and carried out, and with the several parts of the apparatus—namely, the generator, the washer, the scrubber, the filter, and a pump—for inducing a circulation of the gases through 80 the apparatus and onward to their destination and to a compressor coupled in their operative arrangement.

Similar letters and numerals of reference indicate the same parts in the drawings. 85

A indicates a gas-generator provided at its top with a manhole 1 and at its bottom with a manhole 2 for access thereto and with a breaker-wall 3 at the rear of a gas-generating-chamber 4.

90 Into the front of the gas-generating chamber opens an air-supply pipe 5, surrounding an oil or other hydrocarbon pipe 6, in turn surrounding a steam-supply pipe 7, the diameter of the pipe 6 being sufficiently smaller 95 than the pipe 5 to provide a surrounding air-passage and the pipe 7 being of sufficiently less diameter than the pipe 6 to form a surrounding passage for oil, and preferably in practice the pipes 6 7 terminate shortly before reaching the inner end of the pipe 5 for the purposes of promoting a more thorough mixture of the air, steam, and oil before entering the generating-chamber 4. These several supply-pipes may be connected in 100 the usual manner with the sources for their supply, and the oil and air pipe, and particularly the latter two, are preferably connected with means for directing their respective supply thereto under pressure, the said pipes be- 110

ing so arranged relative to the breaker-wall that they shall deliver their supply against the face of the breaker-wall at a right angle thereto and preferably with a force sufficient 5 to first finely divide the materials and in such a manner that they will first be instantly violently exploded and then thoroughly mixed and expanded within the generating-chamber. A short distance below the pipe 5 10 above described is a steam-pipe 8, also projecting through the front of the generating-chamber and in a line opposing and at a right angle to the breaker-wall 3, which pipe 8 serves to supply additional steam in a manner hereinafter described best promoting its 15 decomposition and combination with the mixed gases evolved in the generating-chamber. Peek-holes 9 and 10 are provided at the front of the structure for observing the 20 heats, current, and generation within.

Adjacently forward of the generating-chamber is a chamber B, separated in part from the generating-chamber by a depending wall 11, which extends from the top thereof to a point sufficiently above the bottom to afford a free passage 12 for the gases from the generator to the chamber B and which must therefore first descend through chamber 13 below the generating-chamber before entering 25 the chamber B.

The chamber B is provided with manholes 14 and 15, respectively, at its top and bottom and for access thereto and discharges its gases through a pipe or passage 16 near the 30 top of the generating-chamber into a washer C, which washer may be cylindrical in form, as shown, or of any other desired form. The washer C is provided with a series of downwardly-inclined deflecting-plates 17, set at 35 such an angle that they will shunt water supplied through a pipe 18, entering the top of the washer from one plate to the other and with such force as will prevent any carbon accumulating on the plates, which, together with the water discharging through the pipe 40 18, will subject the gas discharging from the chamber B to the cleansing, cooling, and contracting effect of water baffled and shunted in the direction of its course. The unassociated carbon or tar and other solids extracted in this manner by the washer are deposited by a current of water through a pipe 19 in the bottom of the washer discharged into a trap 20.

55 Adjacent to the washer C is a scrubber D, connected by a pipe 21 with washer C and which is located at a point toward the bottom of the washer and the scrubber, so that gases discharged from the washer must ascend through the scrubber and to a pipe 22 60 near the top thereof before escaping from the latter.

The scrubber is provided with the usual substantially horizontal plates 23, projecting 65 from opposite sides thereof and forming a

zigzag passage for the ascent of the gases and for the descent of water supplied to the scrubber through the pipe 24 in the top thereof, the resulting tar and other solid matter accumulating in the scrubber being discharged 70 through the pipe 25 into a trap 26 and access being had to the scrubber-plate through the usual manholes 23^a.

Pipe 22 is provided with a vertical extension 27, projecting downwardly and preferably centrally of a filter E, but terminating at a point a short distance above the bottom of the filter. The filter E, shown to be of cylindrical but may be of any other desired form, has standing upon its bottom and projecting above the lower end of the pipe 27 pieces of round wood or iron poles or pipes 28, set vertically, filling the space between the pipe 27 and the shell of the filter, the space above the ends of these poles surrounding the 80 pipe 27 up to a point below the discharge-pipe 29 thereof near its upper end, being preferably filled with rye-straw 30, cut about one foot in length and tied in small bundles with the straws set vertically, but may be of other 85 fibrous materials suitable for the same purposes. The tar and other refuse accumulating in the filter E is discharged from the bottom thereof through a pipe 31 into a trap 32, the said filter being also provided with a man-hole 33 for access thereto. The filter-discharge pipe 29 is connected with the suction end of a pump F, and gases entering the pump are discharged through a pipe 34 into a compressor G, and thence onwardly to a 90 gasometer or other storage vessels or directly into the mains, as may be desired. 95

The compressor G comprises a closed receptacle 35, which may be of cylindrical or other form, provided with a discharge-pipe 100 36, in which is a valve 37, which may be used for controlling the degree of pressure to which the gases supplied to the compressor-chamber by the pump F are to be subjected and also to regulate the degree of expansion, and therefore the pressure of the gases in the mains, a storage vessel, or other receptacle 105 into the gases discharged from the compressor. The compressor is also provided with a pipe 38, controlled by a valve 39, through which 110 are discharged waters of condensation resulting from the compression of the gases from the compressing-chamber. The compressor is preferably located in a vat 40 and immersed 115 in water or other cooling medium supplied thereto through a pipe 41, which cooling medium after serving to remove the heats of compression from the gas and correspondingly contracting it is discharged through a pipe 42, controlled by a valve 43. 120

In the practical operation of the apparatus described the pump F is put in motion to induce a current of air into the generator A, and at which time the pipe 5 is open and oil is introduced through the pipe 6 into the 130

generating-chamber. When the chamber 4 and the breaker-wall 3 have been sufficiently heated, steam is injected into the generating-chamber through the pipe 7 under a sufficient pressure to deliver the steam, and also any oil or air discharging from the pipes 5 and 6, or either of them, forcibly with sufficient impact against the heated surface to very finely divide the gas-producing materials into particles so minute as to thereby produce instantaneous gasification immediately followed by a thorough mechanical mixing and complete chemical combination. As fast as the gases are thus generated they are by the action of the pump drawn downwardly through the chamber 13 through the passage 12, whence they must rise in the chamber B to the passage 16 before escaping therefrom. Gases rising in the chamber B after discharging through the passage 16 descend through the washer C, which in the meantime is supplied through the pipe 18 with water sufficient in volume and of a temperature capable of discharging a substantial portion of the heavy hydrocarbons and other solid products from the gas and also from the inclined plates, which heavy hydrocarbons, largely in the form of tar, automatically discharge from the washer through the pipe 19 into the trap 20. The gases are discharged from the washer C through the pipe 21 into the scrubber D, at or near its bottom, and rising upwardly therein in a zigzag manner owing to the arrangement of the horizontal plates 23 against a supply of water through the pipe 24, flowing downwardly from plate to plate in contact with the ascending gases, the accumulating by-products in the meantime discharging through pipe 25 into trap 26. Gases from the scrubber discharge through pipes 22 and 27 to a point at or toward the bottom of the filter and escaping therefrom ascend in contact with and between the poles or rods 28 through the straw filtering material 30, the poles 28 serving as desirable surfaces for collecting and conducting undecomposed materials coming in contact therewith and from the straw to the bottom of the filter, and thereby promoting their collecting therein and discharge therefrom through the pipe 31 into the trap 32. Gases which have passed through the washer, the scrubber, and the filter enter the pump F substantially if not entirely free of all objectionable solids and in this condition may be discharged onwardly to their destination, but under my invention are preferably discharged into the compressor G through the pipe 34 for the purposes of removing condensable vapors therefrom, and thereby reduce the gases discharged from the compressor to a condition for subsequent storing, transportation, and distribution through mains with an entire absence, as near as may be, of their deteriora-

tion either in quality or volume, and this particularly with gas produced from oil, steam, and air.

It is evident that gas generated by the decomposition of the gas materials in the presence of air will contain more or less nitrogen, depending upon the manner of conversion, and it is therefore one of the purposes of this invention to effect a gasification of the gas materials with the least possible quantity of air to avoid an excess of nitrogen and dioxid in the resultant gases, while at the same time dissociating a maximum of steam to combine the thereby-released hydrogen with the volatilized carbon.

I have found by injecting oil and steam simultaneously with a comparatively small volume of air forcibly against a hot surface within a generating-chamber heated within to a gasifying degree that the gasification is instantaneous, and that the conversion of the materials into gas will sustain the heats of the chamber and the surfaces within to the proper degree so long as the materials are so supplied, and that the operation may be continuous without interruption, and that the elements in the gas materials are thus released, and combined within the generating-chamber.

The mixing, baffling, and contact with the surfaces of the breaker-wall and generating-chamber caused by the explosive impact and instantaneous expansion of the forcible discharge against the heated surface of the breaker so sets, combines, and fixes the escaping gases that the customary brick checker-work intervening between the discharge of the generating-chamber and the outlet of the apparatus is dispensed with entirely, and the annoyance and delays caused by the clogging up of the checker-work by carbon or other refractory materials are avoided. This instantaneous conversion of the gas materials into gas in this manner is an important economy in that the saving of the heat by such instantaneous action of the elements necessarily reduces the quantity of air consumed, lessens the resulting nitrogen and the quantity of materials required for heat. A further saving is brought about by so conducting the generated gases as to supply escaping heat to the rear of the breaker and breaker-wall to assist in sustaining the heats of the breaker and generating-chamber, which correspondingly reduces the materials consumed for maintaining a gasifying temperature within the generating-chamber, and thereby the dioxid of combustion and the nitrogen are reduced to a minimum, or, in other words, a uniform and continuous gasifying heat is maintained without interruption with the least expenditure for the necessary heat.

Obviously the washing, scrubbing, filtering and particularly the removal of condens-

able vapors by compression to a degree providing for their storage under high pressure without deteriorating in quantity or volume is not practical in the absence of the production of sufficient fixed gases in the initial generation to insure the commercial success thereof, and with the latter in view it will be apparent that the essential feature of my method consists in subjecting oil and steam 10 to a decomposing degree of heat and concurrently therewith finally dividing their molecules in the presence of each other by forcible impact quickly followed by the explosion of these finely-divided molecules into dissociated gases finally associated together in a volume composed of fixed gases.

The condition precedent to the commercial success for the production of a gas which is free from solids and particularly condensable 20 vapors and by which its compression into minimum space for storage and transportation is practical is the initial generation of a large volume of fixed gas rapidly, continuously, and upon a commercial basis substantially corresponding with that required to produce gases now commonly employed, and this condition precedent is supplied by my invention through the directing of the gas-producing materials with forcible impact against a 30 breaker-wall maintained in a uniformly highly heated condition before discharging into a washer, scrubber, or other device employed for cooling and contracting the gases.

Another important feature accruing to my 35 invention is the method by which the decomposition of an additional—that is to say, an extra—amount of steam may be decomposed and thoroughly combined both mechanically and chemically with the gases of initial 40 generation and which is made possible by discharging such steam within the heats of initial generation and across the path traversed before their escape from the generating-chamber, while at the same time conducting all of 45 the gases in a direction best disregarding their several specific gravities and promoting their association within the generating-chamber before and at the time of their discharge therefrom. Although seemingly to these 50 ends the best results are secured by conducting the generated gases downwardly out of the gas-generating chamber and thence upwardly in contact with the rear surface of the breaker-wall, it will be no substantial departure 55 from the method of my invention to have the gases ascend in escaping from the generating-chamber, provided they are caused to descend in contact with the rear face of the breaker-wall, for, as before intimated, 60 the maintaining of a uniformly-high degree of heat made possible by heating the breaker-wall from both its front and rear sides is desirable and necessary in order to secure the very best results in the initial generation of 65 the gas.

When the gases ascend out of the generating-chamber, it should be observed that if an excess of steam is desirable then the steam-pipe 8 should be in a plane above instead of in a plane below the point at which oil and steam are injected into the generating-chamber against the breaker-wall for the purposes of initial generation.

While an important feature of my invention is the commercially successful production of a dehydrated gas from oil and steam, and therefore a gas which may be stored and transported under excessive pressure and subsequently used at that pressure and a low pressure without precipitation—that is to say, 80 without deterioration in either quantity or volume—my invention is not to be so limited, for it includes the method herein described for the generation of the gas to the exclusion of said subsequent compression and also 85 either or both the washing and scrubbing thereof.

In conclusion, it should be observed that while the apparatus shown and described herein is believed to be the best means by 90 which to perform my methods, it should be understood that my invention is not limited thereby, for it includes any apparatus, however different it may be in mechanical construction, in which it is possible or practical 95 to perform the same or substantially the same methods herein described and claimed.

Having thus described my invention, what I claim as new therein, and desire to secure by Letters Patent, is—

1. The herein-described method of producing illuminating and heating gas, the same consisting in conducting gas-producing materials forcibly through a decomposing degree of heat in a generating-chamber, then subjecting said material to a violent impact finely dividing the molecules thereof, and concurrently therewith to a decomposing degree of heat dissociating their gases, then confining said gas within said heat until 110 reassociated into a volume of fixed gas, then supplying steam thereto, and finally conducting said gases out of said chamber, whereby heats of generation are produced and utilized for sustaining a decomposing 115 degree of heat in a generating-chamber, and illuminating and heating gases containing an excess of decomposed steam are continuously produced within the confines of a generating-chamber, substantially as described.

2. The herein-described method of producing illuminating and heating gas, the same consisting in conducting gas-producing materials forcibly through a decomposing degree of heat in a generating-chamber, then subjecting said materials to a violent impact finely dividing the molecules thereof, and concurrently therewith to a decomposing degree of heat dissociating their gases, then confining said gases within said heat until 130

reassociated into a volume of fixed gas, and finally supplying additional steam thereto across the path of the discharge of the gas from the generator approximately about the 5 point of the exit of the gases from the generator, substantially as described.

3. The herein-described method of producing illuminating and heating gas, the same consisting in conducting gas-producing materials forcibly through a decomposing degree of heat in a generating-chamber, then subjecting said materials to a violent impact finely dividing the molecules thereof, and concurrently therewith to a decomposing 10 degree of heat dissociating their gases, then confining said gases within said heat until reassociated into a volume of fixed gases and 15 finally delivering across the path of the gases at about the point of their discharge from the retort, additional steam forcibly delivered with a violent impact finely dividing the molecules thereof in the presence of a de- 20 gree of heat dissociating the gases of such steam and promoting their mixing with the gases of primary generation, whereby heats of generation are produced and utilized for combining additional hydrogen and oxygen 25 with illuminating and heating gases in the continuous production thereof, substantially as described.
4. The herein-described method of producing illuminating and heating gases, the same consisting in conducting oil, steam and air simultaneously forcibly through a decomposing degree of heat in a generating-chamber, then subjecting said materials in the presence of each other to a violent impact 30 finely dividing the molecules thereof and concurrently therewith to a decomposing degree of heat dissociating their gases, then confining said gases within said heat until reassociated into a volume of fixed gas, then 35 discharging these gases out of said chamber and finally conducting additional steam across the path thereof during said discharge and subjecting said steam to violent impact in the presence of said discharging gases, 40 whereby an excess of steam is continuously decomposed subsequently mixed and combined with fixed hydrocarbon gases discharging from a generating-chamber, substantially as described.
5. The herein-described method of producing illuminating and heating gases, the same consisting in conducting gas-producing 45

materials forcibly through a decomposing degree of heat in a generating-chamber, then subjecting said materials to a violent impact 50 finely dividing the molecules thereof and concurrently therewith to a decomposing degree of heat dissociating their gases, then confining said gases within said heat until reassociated into a volume of fixed gases and 55 finally delivering across the path of the gases at about the point of their discharge from the retort, additional steam forcibly delivered with a violent impact finely dividing the molecules thereof in the presence of a de- 60 gree of heat dissociating the gases of such steam and promoting their mixing with the gases of primary generation, whereby heats of generation are produced and utilized for combining additional hydrogen and oxygen 65 with illuminating and heating gases in the continuous production thereof, substantially as described.

6. The herein-described method of producing illuminating and heating gas, the same consisting in conducting oil, steam and air simultaneously forcibly through a decomposing degree of heat in a generating-chamber, then subjecting said materials in the presence of each other to a violent impact 70 finely dividing the molecules thereof and concurrently therewith to a decomposing degree of heat dissociating their gases, then confining said gases within said heat until reassociated into a volume of fixed gas, then 75 discharging these gases out of said chamber and finally conducting additional steam across the path thereof during said discharge and subjecting said steam to violent impact in the presence of said discharging gases, 80 whereby an excess of steam is continuously decomposed subsequently mixed and combined with fixed hydrocarbon gases discharging from a generating-chamber, substantially as described.
